CLAIM

The ornamental design for a snowguard, as shown and described.

DESCRIPTION

FIG. 1 is a top front left perspective view of a snowguard in accordance with one embodiment of the present invention. FIG. 2 is a top rear left perspective view thereof.

FIG. 3 is a bottom rear right perspective view thereof.

FIG. 4 is a front elevation view thereof.

FIG. 5 is a rear elevation view thereof.

FIG. 6 is a right side elevation view thereof, with the left side being a mirror image thereof.

FIG. 7 is a top plan view thereof.

FIG. 8 is bottom plan view thereof.

FIG. 9 is a top rear left exploded perspective view thereof. FIG. 10 is a bottom rear right exploded perspective view thereof.

FIG. 11 is a top front left perspective view of a snowguard in accordance with another embodiment of the present invention.

FIG. 12 is a top rear left perspective view thereof.

FIG. 13 is a bottom rear right perspective view thereof.

FIG. 14 is a front elevation view thereof.

FIG. 15 is a rear elevation view thereof.

FIG. 16 is a right side elevation view thereof, with the left side being a mirror image thereof.

FIG. 17 is a top plan view thereof.

FIG. 18 is bottom plan view thereof.

FIG. 19 is a top rear left exploded perspective view thereof; and,

FIG. 20 is a bottom rear right exploded perspective view thereof.
